UNITED STATES PATENT OFFICE.

CHRISTIAN E. MUUS, OF BROOKLYN, NEW YORK.

LUBRICATING DEVICE FOR WATCHES.

Application filed November 19, 1921. Serial No. 516,372.

To all whom it may concern:

Be it known that I, CHRISTIAN E. MUUS, a citizen of the United States, residing at Brooklyn, in the county of Kings and State of New York, have invented new and useful Improvements in Lubricating Devices for Watches, of which the following is a specification.

This invention relates to lubricating devices and particularly to one designed for use in connection with watches or like instruments which are usually enclosed in a case, and an object of the invention is to provide a device that can be saturated with a lubricating and cleansing liquid or solution, which, due to the form and construction of the device will retain a certain amount of lubricating liquid and cause same, by a process of evaporation, to impregnate or saturate the air around the works of the watch and thereby act to automatically supply the said works with a correct quantity of lubricant that will insure the works against premature deterioration, and permit the works to perform their necessary function without undue stoppage or interruption.

A still further object of the invention is to provide a simple device of this character which will consist of a plurality of disks or membranes associated so that when saturated with a lubricating solution, the solution will be held in cellular formation between the disks or membranes and the supply of liquid preserved or retained for a relatively long period of time.

Another object of the invention is to provide a lubricating device that can be conveniently arranged in an ordinary watch case and completely enclosed thereby so that by a process of evaporation induced by natural conditions, the works of the watch will be amply supplied with lubricant.

With the above and other objects in view which will appear as the nature of the invention is better understood, the same consists in the improved construction and novel arrangement of parts which will hereinafter be fully described and particularly pointed out in the claims.

In the accompanying drawing, has been illustrated, a single and preferred form of the invention, it being, however, understood that no limitations are necessarily made to the precise structural details therein exhibited, but that changes, alterations and

modifications within the scope of the claims may be resorted to when desired.

Figure 1, is a perspective view of the device.

Figure 2, is a conventional illustration showing a watch in section with the lubricating device mounted in the case of the watch.

Figure 3, is a section through the device conventionally illustrating the method of trapping the liquid lubricant to present the cellular retention of the lubricant.

In carrying the invention into practice, use is made of a plurality of tissue paper disks, 5, which are preferably stitched or otherwise suitably secured together as at 6. This arrangement of securing the disks together exposes the spaces between the several disks at the periphery of the structure. As stated, tissue paper is preferably employed and I find that a paper glazed upon one side is well adapted to the purpose of the invention. These disks are superimposed relatively as a result of the aforesaid mode of binding them together and they are adapted to be saturated or supplied with a suitable commercial lubricant or cleansing solution which will collect and be maintained in cellular formation between the respective disks. This is shown in the conventional illustration in Figure 3, of the drawing.

By providing disks of tissue paper, either glazed on one side or on both, a proper retention of the lubricant is provided for and in practice, the device, when arranged within the case of a watch will effectively function as a lubricator for a relatively long period of time. It is of course reasonable to believe that the more of these disks that are bound together, the greater the charge of lubricant carried thereby. This, I of course can vary within the scope of the appended claims. By providing glazed tissue paper disks, I prevent rapid absorption or evaporation of the lubricating fluid. However, I do not wish to be entirely limited in this respect. I have, however, experimented with various forms of materials such as blotting paper, textile materials and the like and of this collection, find the aforesaid glazed paper most suitable for my purpose.

The device is arranged in a compact package and is adapted to be placed in a watch case as shown in Figure 2, so as to be in-

terposed between the back of the case and the exposed works of the watch. By enclosing the device in the case, the atmospheric air in circulation around the works is saturated or impregnated by the natural process of evaporation and in consequence thereof, the works of the watch are, for all intents and purposes, constantly bathed in this vaporized air. Care should be exercised in the selection of a proper kind of lubricating liquid so that undue charges of gum or foreign substances will not be carried into the active operating parts of the watch works. There are many standard or well known lubricating solutions that can be used for this purpose. When the device is arranged between the back or cover section of the watch case, and the open side of the watch works, the joint between the said back of the case and the front part thereof is sealed to an appreciable extent and foreign particles arrested by the device as will be understood.

I have found that by mixing fifty per cent lubricating oil with fifty per cent kerosene, the device acts both as a cleanser and as a lubricator. I do not wish to be

limited in this respect, however, as other well known solutions can be employed in lieu thereof.

30

What is claimed as new is:—

1. A lubricating device for watches comprising a plurality of disks bound together centrally thereof and saturated in a lubricating solution.

35

2. As a new article of manufacture, a lubricating device consisting of a plurality of tissue paper disks saturated in oil and secured together centrally thereof to space the disks at their peripheries.

40

3. As a new article of manufacture, a watch lubricator comprising a plurality of identically formed disks secured together centrally thereof to space the disks at their peripheries designed to fit within a watch case and saturated with a liquid lubricating solution so that charges of the solution will be held in cellular formation between the disks subject to being cast off by the natural process of evaporation.

45

In testimony whereof I have affixed my signature.

50

CHRISTIAN E. MUUS.
